UNITED STATES PATENT OFFICE.

ESTELL C. RANEY, OF COLUMBUS, OHIO, ASSIGNOR TO THE AUTOMATIC RECLOSES CIRCUIT BREAKER COMPANY, OF COLUMBUS, OHIO, A CORPORATION OF OHIO.

AUTOMATICALLY-RECLOSES CIRCUIT-BREAKER.

1,273,786.

Specification of Letters Patent. Patented July 23, 1918.

Application filed August 17, 1916. Serial No. 115,856.

To all whom it may concern:

Be it known that I, ESTELL C. RANEY, a citizen of the United States of America, residing at Columbus, in the county of Franklin and State of Ohio, have invented certain new and useful Improvements in Automatically-Reclosing Circuit-Breakers, of which the following is a specification.

My invention relates to automatically closing circuit breakers, of a type peculiarly effective in the protection of motor circuits and particularly desirable in individual motor circuits.

In the operation of a motor, it is desirable that a starting resistance be in circuit at the instant of applying power to start the motor. Therefore, I have provided an overload circuit breaker that cannot reclose until this starting resistance has been rendered effective, but which recloses automatically after such resistance has been rendered effective. My circuit breaker is automatic, and may be so connected with any standard form of controller or starting device that the breaker can only reclose after such controller has been returned to "off" position to cut in the starting resistance. Then, the operation is such that the operator need not remove his hand from the controller; but, during the normal movements of the controller and after the starting resistance has been rendered effective, the circuit breaker automatically recloses. Thus, the operator is not called upon to depart in any measure from his customary procedure except that it is imperative for him to move the controller to "off" position; otherwise the circuit breaker will not operate.

My invention further comprises a circuit breaker adapted to be used in connection with controlling devices, the said breaker being responsive to overload, or failure of voltage, or to other conditions under which it may be desirable to open the circuit. For instance, this breaker may be used in conjunction with a controller having an auxiliary contact, which auxiliary contact controls the operation of the main contacts of the circuit breaker, so that such breaker will make and break the motor circuit outside of the controller at each cycle of operation of the controller. Or, my breaker may be used in connection with con-

trollers or starting boxes, so that the breaker does not ordinarily open except in response to overload, or failure of voltage.

It is desired to call particular attention to the fact that the circuit breaker in my improvement may be made inaccessible since its reclosing is entirely dependent upon the return of the controller to "off" position. Therefore, the setting and operation of my breaker cannot be interfered with by the operator. On the other hand, the very fact that the reclosure of my breaker is governed by the controller broadens its scope of adaptability, since it may be used in protecting apparatus where the circuit breaker is necessarily remote from the controller, and yet the operator need not leave his controller.

I have deemed it advisable to describe my invention in its application to both the classes of mechanism indicated above, and its preferred embodiment is shown in the accompanying drawings wherein similar characters of reference designate corresponding parts, and wherein—

Figures 1, 2 and 3 illustrate my improvement in application to a motor controller having an auxiliary contact device for making and breaking the motor circuit outside of the controller.

Figs. 4, 5 and 6 show my improvement in conjunction with a controller having manually operated contacts and without an auxiliary contact device.

Fig. 1 diagrammatically illustrates the position of the parts of my apparatus with the circuit breaker closed.

Fig. 2 diagrammatically illustrates the position of the parts immediately after an overload, and with the motor controller in "running" position.

Fig. 3 illustrates the position of parts of my apparatus, immediately after the return of controller to "off" position and with the mechanism set for instantaneous operation upon the return of the controller to "starting" position.

Fig. 4 shows my apparatus with the circuit breaker closed, when used with a controller without an auxiliary contact.

Fig. 5 shows the position of parts immediately after an overload, with the motor controller in "running" position.

Fig. 6 shows the position of parts immediately after the return of controller to "off" position.

In the drawings and referring particularly to Figs. 1, 2 and 3, the main feeder wires are designated 1 and 2. The motor is designated M, the circuit breaker main contact is designated 4, and its reclosing coil is designated 8. The motor controller may have its parts indicated 29, 30, 31, 32 and 33. In conjunction with the controller an auxiliary contact device is indicated at 15 and 16.

The circuit of coil 8 is under the control of a pivoted switch member 12, which is designed to make contact with either of the points 11 and 20. Switch 12 also carries an extended arm subject to the lifting action of the core 18 of an overhead coil 6. Coöoperating with switch 12 is also a latch 19, having a spring 38. This latch 19 is designed to hold the switch member 12 in engagement with contact point 20. Coil 24 provides a means of release for latch 19.

It should be particularly noted that with the switch member 12 in contact with point 20, Fig. 2, that two parallel paths exist between the wires 22 and 17, one of the circuits being through coil 24 and the other circuit being a low resistance circuit through wire 14, to auxiliary contact device 15 and 16. This latter circuit is broken by the movement of controller to "off" position.

The operation of my circuit breaker, when used as shown connected in Figs. 1, 2 and 3, may be briefly stated as follows:—Assuming the feeders 1 and 2 to be energized, a movement of the controller to position as shown in Fig. 1, completes the circuit for operating coil 8. The main circuit breaker contact 4 is closed by the operation of this coil 8, and the motor is supplied with current through wire 3, through contact 4, wire 5, series coil 6, controller parts 31, 32 and 33.

The circuit of coil 8, is traced from wire 1, through wire 3 to coil 8, resistance 9, wire 10, contact 11, switch 12, wires 13, and 14, auxiliary contact device 15 and 16, to wire 17, thence to wire 2. In case of an excessive flow of current through coil 6, the plunger 18 is raised, engaging extension of switch 12, and rotating this switch out of contact with the point 11, and into engagement with contact point 20. Latch 19 engages 12 and maintains it in contact with 20 until released by action of coil 24. The movement of switch 12 out of contact with point 11 results in the opening of breaker and the parts assume the position indicated in Fig. 2. A circuit now exists through limiting resistance 21, to wire 22. From wire 22, a circuit exists through wire 13, switch 12, contact 20, coil 24, wire 25, to wire 17. In shunt with this last named circuit, is another circuit of much lower resistance by way of wire 14, contact ring 15, and contact arm 16 to

wire 17. It is obvious that so long as the arm 16 is in contact with ring 15, that the coil 24 will have practically all its current shunted away. Upon return of controller to "off" position, this shunt circuit is broken by the separation of 15 and 16, so that the entire current flowing through 21 will now pass through coil 24, and energize it sufficiently to raise its core 28 to engage and release latch 19. This results in the return of parts to positions as shown in Fig. 3. A movement of the controller handle to the starting position, will now result in the re-closure of the breaker.

The connections shown in Figs. 4, 5 and 6 show the application of this breaker to a motor circuit having a manually operated controller of the drum type.

It should be noted that in this case the coil 24 is shunted by the wire 38, wire 7, and controller 32. The resistance of this shunt circuit is very low in comparison to the resistance of coil 24.

The operation of my circuit breaker with the connections as shown in Figs. 4, 5 and 6, may be described as follows:—Referring to Fig. 4, operating coil 8, is energized by current from feeder 2, through wire 42, resistance 9, wire 10, contact 11, switch 12, wire 27, and wire 3 to feeder 1. With coil 8 energized, contact 4 will be closed and the path of current to the motor will be through wire 3, contact 4, wire 5, overload coil 6, controller parts 31, 32 and 33, wire 43, the motor, wire 44, to line 2.

Should an overload current flow through the motor, coil 6 will be energized to propel its core 18 upward and cause switch 12 to be rotated out of contact with 11 and into contact with 20, in which position it will be held by latch 19, until said latch is released by the action of coil 24. This position of parts is indicated in Fig. 5, in which the circuit of the operating coil is shown open between 11 and 12, with a consequent opening of main contact 4, and a circuit completed from feeder 1, through wire 27, switch 12, resistance 37, coil 24, wires 41 and 43 through motor to wire 2, by wire 44.

Owing to the low resistance shunt path around coil 24, by way of wire 38, and through controller, practically all of the current through resistance 37 will be shunted around coil 24, so long as the controller is in starting or running position. Upon a return of the controller to "off" position, the shunt circuit around coil 24, is interrupted and all the current passing through the limiting resistance 37, will flow through coil 24, and cause its plunger 28, to engage and release latch 19. The parts will then assume the position shown in Fig. 6. The circuits are now complete, so that the motor may be started by the usual movement of the controller.

- In the foregoing description, I have described two methods of connecting my circuit breaker to two different forms of motor controllers, utilizing the same principle in each case, namely, that of having the reclosing means under the control of two parallel circuits, one of which is completed by the controller when in the starting or running position.
- 5 10 This same principle may be applied to connect my circuit breaker to operate with practically any form of motor controlling device, without any change of mechanical details on said motor controller.
- 15 Having thus described my invention, what I claim is:
1. In combination with a current controlling device adapted to control the flow of current through a circuit, a circuit breaker, 20 reclosing means, mechanism for restraining said reclosing means, means comprising a releasing coil for releasing said restraining means when the current controlling device is made to open the circuit in which it is connected, a limiting resistance in circuit with the releasing coil, and a circuit in parallel with the releasing coil, a part of said parallel circuit being through the controlling device, so that said last named circuit is open 25 when the controller is moved to "off" position.
  2. In combination with a circuit controlling device adapted to control the flow of current through a circuit, a circuit breaker, 30 reclosing means, mechanism for restraining
- said reclosing means, means for releasing said restraining means, said controlling device and said releasing means being in parallel whereby circuit through said device shunts current away from said releasing means which is thus rendered inoperative until the circuit through said controlling device is opened.
3. In combination with a current controlling device adapted to control the flow of current through a circuit, a circuit breaker, 40 reclosing means, mechanism for restraining said reclosing means, means for releasing said restraining mechanism, switch structure operative upon overload to render said restraining means effective and simultaneously render said releasing means operable, means for operating said releasing means upon the opening of the circuit by the controlling device.
4. In combination with a current controlling device adapted to control the flow of current through an electric circuit, a circuit breaker, a coil for closing said circuit breaker, a switch for opening the circuit of 45 said closing coil, restraining means for said switch, a coil to release said restraining means, said switch being operative to close the circuit of said releasing coil, an overload coil controlling the opening of 50 said switch, said releasing coil governing closing of said switch.
- 55 In testimony whereof I hereby affix my signature.

ESTELL C. RANEY.
